[57] CLAIM

The ornamental design for a cover for a linear actuator for an earth station satellite receiving antenna, substantially as shown.

DESCRIPTION

FIG. 1 is a top, front and right side perspective view of a cover for a linear actuator for an earth station satellite-receiver antenna showing my new design;

FIG. 2 is a right side elevational view thereof, the left side elevational view being a mirror image;

FIG. 3 is a top plan view thereof, the bottom being a mirror image thereof;

FIG. 4 is a front elevational view thereof; and

FIG. 5 is a rear elevational view thereof.
The broken line showing of the linear actuator in FIG. 1 is for illustrative purposes only and forms no part of the claimed design.

FIG-1

FIG-2

FIG-3

FIG-4
